UNITED STATES PATENT OFFICE.

WALTER A. BOCKIUS, OF WILMETTE, ILLINOIS, ASSIGNOR TO TIDEMAN, WHETTER, BOCKIUS, A COPARTNERSHIP CONSISTING OF H. F. TIDEMAN, H. H. WHETTER, AND W. A. BOCKIUS, OF CHICAGO, ILLINOIS.

ELECTRICAL CONDENSER.

Application filed June 6, 1925. Serial No. 35,458.

The invention relates to electrical condensers and more particularly to that type in which two sets of interleaved plates are conjointly shifted to increase or decrease the lapped areas of the plates.

One object of the invention is to provide improved means for relatively shifting the interleaved plates and to dispense with gears for that purpose. Another object of the invention is to provide improved shifting means for the plates of an electrical condenser.

Other objects will appear from the specification.

15 The invention consists in the several novel features hereinafter set forth and more particularly defined by claims at the conclusion hereof.

In the drawings: Fig. 1 is a plan of a condenser embodying the invention. Fig. 2 is a transverse section of the condenser, the plates being shown in their unlapped position of Fig. 1. Fig. 3 is a section on line 3-3 of Fig. 1. Fig. 4 is an axial section 25 through the cam for shifting the plates. Fig. 4^a is a detail section showing the vernier adjustment for operating the cam disk when desired.

The invention is exemplified in a device 30 comprising a supporting bracket 6, which is adapted to be clamped against the inner face of a suitable panel 5 by a nut 7 which is threaded to a bearing sleeve 9 which extends through the bracket and panel and is enlarged at its front end to abut against the panel. A pair of fixed shafts 10 and 11 are each suitably secured in bracket 6 to pivotally support a pair of sets of interleaved plates 13 and 14. The plates 13 are fixed in 35 kerfs in an arm 16 of a hollow shaft or sleeve 17, which is free to swing on the fixed shaft 10, and held against inner endwise displacement by a nut 18. Plates 14 are interleaved with plates 13, are similarly secured 40 to an arm 19 of a hollow shaft 20, which is pivoted on fixed shaft 11, and held against inner endwise displacement by a nut 18.

The operative area of both sets of plates is substantially square, and the axes about 45 which the sets of plates swing are located at points adjacent opposite sides of the plates, so that the latter will swing between them. These points are corelatively disposed and

corelated with the operative area of the plates, so that the diagonally opposite corners of the plates will be substantially coincident when the plates are in non-active or non-lapped relation, as shown by dotted lines in Fig. 2, and so that the plates will be shifted diagonally with respect to one another, until all corners thereof are coincident and the plates are thoroughly lapped to provide the maximum condensing capacity. In moving into and out of lapped relation the parallelism of the sides of the square plates 65 is substantially maintained, so that the lapping areas are increased or decreased in substantially square uniform progression to correspondingly increase or decrease the capacity of the condenser in accordance with 70 the requirement in tuned radio frequency circuits.

The improved mechanism for conjointly and equidistantly shifting the sets of plates comprises an arm 22 which is suitably fixed 75 to hollow shaft 17 of plates 13 and a similar arm 23 which is suitably fixed to the shaft 20 of plates 14, and a rotatable disk 24 of insulating material. The inner end of each of the arms 22, 23 has suitably secured thereto 80 a stud 30 and these studs are adapted to travel respectively in spiral cam grooves 25 and 26 formed in the inner face of the disk 24, so that as the disk is rotated, the arms 22 and 23 will swing oppositely between 85 shafts 17 and 20. Disk 24 is fixed to shaft 27, which extends through the bearing sleeve 9, and has attached to its front end a suitable knob 28, whereby it may be manually 90 rotated to shift the disk and operate the plates 13 and 14. An index or pointer 29 is fixed to the knob 28, and is adapted to indicate the degree of rotation and the corresponding positions of the condenser plates 95 on a suitable dial, usually fixed to the front of the panel 5. This dial is usually marked to indicate degrees or calibrations, to indicate the cooperative position of the plates. The studs 30 are preferably tapered and 100 the cam grooves 25 and 26 are similarly tapered to provide a snug fit between the studs and the grooves. Spring washers 33 are interposed between the nuts 18 and the shafts 17 and 20 respectively, to frictionally hold the plates in their assigned positions. 105 When the disk is rotated, the cam grooves 25

means of this key the shaft section 15 is rotated until the proper date appears in the sight-aperture 56.

However, this rotation causes the unwinding of the power-spring 28, and the latter must be wound up again by inserting the same set-key 119 in the hollow portion 68 of the winder-shaft 62. For this purpose, the set-key is also provided with a crown 121 upon which are cut suitable teeth to fit those on the shaft portion 69.

The time required for making the above changes or adjustments amounts to only a few minutes, generally. But, in the meantime, the center-shaft 83 and its sprocket 84 of the alarm-clock keep on turning slowing, so that when the inner casing is again inserted in place, the spring extension 96 may not readily engage one of the spaces between the rectangular clutch-teeth 90. When the lapse of time is short, no further adjustment need be made, as this extension will soon engage one of said spaces and it is of no great importance whether or not the change of date be made a few minutes before or after midnight.

If the calendar mechanism has been disconnected too long from the alarm clock, it becomes necessary to make adjustments to the calendar-shifting mechanism also. This may be done by using the same set-key 119 on the clutch-teeth 90 or, preferably, by rotating the crown-gear 99 by hand until the actual hour of the day at which this regulating is being done, as read on the graduations 103, appears in line with the pointer 104. When so adjusted, the change of date will occur at midnight.

The arrangement shown in Figs. 1 to 3 enables the application of my invention in connection with old alarm-clocks or other similar clocks. More pretentious effects are obtained in the embodiment illustrated in Fig. 4 wherein a complete calendar mechanism would be assembled in a drawer-like container 122 provided with a pull knob 123, and which would correspond to the inner casing mentioned hereinbefore. The construction of the interior mechanism would be the same as above described, except for minor changes required by the shape of the outer casing.

Also, if desired, the calendar ribbon may

have printed thereon, in addition to the dates, supplementary matter such as historical or religious holidays, etc., corresponding to the various dates.

As will be understood, as suggested herein, there may be slight changes made in the construction and arrangement of the details of my invention without departing from the field and scope of the same, and I intend to include all such variations, as fall within the scope of the appended claims, in this application in which the preferred form only of my invention has been illustrated and described.

I claim:—

1. In a clock operated calendar, a supply reel; a calendar-ribbon wound thereon; a wind-up reel and a spring operated mechanism adapted for winding said ribbon from said supply-reel onto said wind-up reel; a plurality of guide-rolls and a pressure-roll positioned intermediate said reels and engaged by said ribbon, and a release mechanism adapted to periodically release a definite portion of said ribbon onto said wind-up reel, said release mechanism comprising a stop-pin positioned on the shaft of said pressure-roll, an escapement-disc and clock operated means for periodically rotating said escapement-disc.

2. In a clock operated calendar, a supply reel; a calendar-ribbon wound thereon; a wind-up reel and a spring operated mechanism adapted for winding said ribbon from said supply-reel onto said wind-up reel; a plurality of guide-rolls for said ribbon; a pressure roll adapted to exert a yielding pressure upon one of said guide-rolls and to be rotated by said ribbon; a shaft for said pressure-roll; a stop-pin positioned on said shaft and adapted to prevent the rotation thereof; an escapement-disc comprising a plurality of inclined sectoral vanes adapted to be engaged by said stop-pin, and clock operated means for periodically releasing the engagement between said stop-pin and escapement-disc to permit the rotation of said friction-roll for the purpose of winding a definite portion of said ribbon on said wind-up reel.

In testimony whereof I affix my signature.

FRANK NEDBALEK.
